US00D622724S

(12) **United States Design Patent**
Burke et al.

(10) **Patent No.:** US D622,724 S
(45) **Date of Patent:** ** Aug. 31, 2010

(54) **DATA INPUT AND GAME CONTROL DEVICE**

(75) Inventors: **Michael Burke**, Calgary (CA); **Nino Calderola**, Winnipeg (CA)

(73) Assignee: **Cyberhand Technologies International, Inc.**, Henderson, NV (US)

(**) Term: **14 Years**

(21) Appl. No.: **29/325,788**

(22) Filed: **Oct. 6, 2008**

(51) LOC (9) Cl. **14-02**

(52) U.S. Cl. **D14/400**; D14/218; D21/333

(58) **Field of Classification Search** D14/217, D14/218, 356, 388, 399-401, 412-416, 432, D14/434, 454-457, 496; D21/324, 332, D21/333; 463/1, 30, 36-38, 46, 47; 345/156-161, 345/905

See application file for complete search history.

(57) **CLAIM**

The ornamental design for a data input and game control device, as shown and described.

DESCRIPTION

FIG. 1 is a perspective view of a data input and game control device, embodying our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.
